UNITED STATES PATENT OFFICE.

NIELS A. CHRISTENSEN, OF MILWAUKEE, WISCONSIN.

STARTING APPARATUS FOR INTERNAL-COMBUSTION ENGINES.

Application filed March 19, 1921. Serial No. 453,798.

To all whom it may concern:

Be it known that I, NIELS A. CHRISTENSEN, a citizen of the United States, residing at Milwaukee, in the county of Milwaukee 5 and State of Wisconsin, have invented certain new and useful Improvements in Starting Apparatus for Internal-Combustion Engines, of which the following is a specification, reference being had to the accompanying drawing, forming a part thereof.

This invention relates more particularly to starting apparatus of the type shown and described in Letters Patent issued to me 15 June 16, 1916, No. 1,185,874, and January 15, 1918, No. 1,253,669, such apparatus employing an explosive mixture of air and oil or other fluid fuel and comprising the usual or any suitable ignition system, a reservoir 20 for compressed air, a compressor for charging the reservoir, a carburetor for producing the requisite explosive mixture of air and fuel, distributing valve mechanism for admitting charges of the explosive mixture 25 under pressure to the engine cylinders at the beginning of the firing or working strokes of the pistons, and a driver's valve controlling the connections of the compressor and distributing valve mechanism with 30 the reservoir.

The main objects of the present invention are to facilitate installation of the apparatus in motor vehicles and with engines of different kinds and makes; to afford easy 35 access to internal parts of the apparatus, particularly of the compressor, for inspection, repair or renewal without disturbing the mounting of the apparatus as a whole; to simplify and improve the construction 40 and operation of the distributing valve mechanism and avoid unnecessary wear thereof; to facilitate timing the distributing valve mechanism for installation with engines of different kinds, so that the apparatus can be assembled in the factory where 45 it is made for any given engine and afterwards mounted on such engine by others without taking the apparatus apart; to enable the apparatus as a unit to be mounted 50 on an engine in the place of the ordinary magneto and connected with the magneto to the same driving shaft without retiming the magneto; to prevent assembling the rotary distributing valve and the shaft or member 55 which drives it in any but the correct angular relation to each other; to automatically

control the operation of the compressor according to the pressure which it produces; to maintain the requisite pressure in the compressed air reservoir without special 60 care or attention; to maintain an adequate and substantially constant supply of oil or liquid fuel for carbureting the compressed air as it passes through the apparatus to the engine; to avoid injury to the carburetor 65 float and interference with its proper operation by subjecting it to the starting pressure; to prevent flooding of the apparatus with the liquid fuel; to automatically lubricate the working parts of the apparatus 70 from a connection with the ordinary lubricating system of the engine with which it is installed; and generally to simplify and improve the construction and operation of starting apparatus of the type to which the 75 invention pertains.

The invention consists in the construction, arrangement and combination of parts as hereinafter particularly described and pointed out in the claims. 80

In the accompanying drawing like characters designate the same parts in the several figures.

Figure 1 is a general view in side elevation, of starting apparatus embodying the 85 invention as applied to a typical four-cylinder engine, in connection with a magneto in the usual place of which the starter unit is mounted; Fig. 2 is an enlarged vertical longitudinal section on the line 2-2, Fig. 90 3, of the starter unit, comprising a compressor, compressor governor or controller, distributing valve mechanism, carburetor and drive connections; Fig. 3 is a vertical cross section of the starter unit on the line 3-3, Fig. 2; Fig. 4 is a detail side elevation of the reversible closure and bearing member 95 and lubricant supply connection which is attached to the right hand side of the starter unit, as shown in Fig. 3; Fig. 5 is an end elevation of the starter unit as viewed from the right relative to Fig. 2, and a vertical cross section on the line 5-5 of the same figure, of the distributing valve; Fig. 6 is a partial vertical cross section on the line 100 6-6, Figs. 1 and 2, the distributing valve case being removed; Fig. 7 is a section on the line 7-7, Fig. 5, of the distributing valve and adjacent part of the main case section; Fig. 8 is an outside face view of the 105 distributing valve seat; Fig. 9 is an inside face view of said valve seat; Fig. 10 is an

inside face view of the distributing valve disk; Fig. 11 is an inside face view of the locking washer for the valve disk; Fig. 12 is an enlarged vertical section on the line 5 12-12, Fig. 3, of the compressor governor or controller; Fig. 13 is a similar view of the driver's or controlling valve; Fig. 14 is a similar view of the float chamber of the carburetor; Fig. 15 is an end elevation of the 10 crank case of the compressor as viewed from the left relative to Fig. 2, with the cover removed; Fig. 16 is a plan view of a modified construction of the starter unit having the carburetor float chamber formed therein; and Fig. 17 is a vertical cross section thereof on the line 17-17, Fig. 16.

Referring to Fig. 1, the apparatus comprises a compressor, a distributing valve, a carburetor, a compressor governor or controller, and a through drive shaft assembled for mounting as a unit in the place of the usual magneto 1 and driven from the same shaft, as for example, the pump shaft of the engine, with which the drive shaft is 25 connected at one end, the magneto being connected with the other end of said drive shaft, and mounted with the starter unit on the same bracket or base plate 2, which may be adapted for attachment to engine bases 30 or frames of different makes or kinds.

In addition to said unit the apparatus comprises a compressed air reservoir 3, and a driver's valve controlling the connections between the reservoir, compressor, distributing 35 valve and compressor governor.

Referring to Figs. 2 and 3, in connection with Fig. 1, the compressor comprises a cylinder 4, removably mounted on the upper side of a crank and clutch case 5, and provided with a piston 6, which is connected by a rod 7 with a crank 8 provided with bearings 9 and 10 in the crank and clutch case.

The crank and clutch case is formed as shown in Figs. 2 and 15, with an opening 45 in the outer end and with an opening in the upper side merging with the end opening into the crank chamber 12, and the end opening is provided with a removable cover 13, in which the crank bearing 10 is fitted and held in axial alignment with the bearing 9. The cylinder 4 communicates at its lower end with the crank chamber 12 through the opening in the upper side thereof, and is provided at its upper end with an automatic discharge valve 14, and between its ends with air intake openings 15.

The chamber of the discharge valve is connected, as shown in Fig. 1, by a pipe 17 with a driver's or controlling valve 18, which in turn is connected by a pipe 19, with the reservoir 3.

The crank and clutch case 5, which is formed as shown in Figs. 2 and 3, with a longitudinal bore in axial alignment with the crank bearings 9 and 10, is removably

bolted or fastened to an upward extension of a main case or carburetor section 21 of the starter unit, with which it forms a gear case or chamber 22. The main case section 21 is formed with an extended mounting base which is fastened to the bracket or base plate 2, as shown in Fig. 1, and with a fuel oil or carburetor chamber 23, extending into the upward extension of the case section on each side of the gear chamber 22, as shown in Fig. 6. A primary drive shaft 25 is journaled in the crank and clutch case 5 and in the upward extension of the main case section 21, in axial alignment with the crank bearing 9, and is provided with a gear 26. A secondary drive shaft 27 is journaled in the main case section 21, below and parallel with the shaft 25, and is provided with a pinion 28, meshing with the gear 26. The shaft 27 passes through and has bearings in a sleeve 29 and removable cover 30 of the case section 21, as shown in Fig. 2. At its ends the shaft 27 is provided with members 32 and 33, of Oldham or flexible couplings, which are set at right angles to each other for connection with a shaft such as the pump shaft 34 of an engine, and the magneto 1, as shown in Fig. 1, so that in mounting the starter unit in the original position of the magneto and connecting them with each other and with the pump shaft, retiming of the magneto is avoided. The sleeve 29, which encloses a part of the shaft 27 and separates it from the carburetor chamber 23, opens at one end into the gear chamber 22. Felt or packing washers 35, inserted in recesses in the cover 30, and in the outer end of the sleeve 29, prevent leakage of lubricating oil from the case at the ends of the shaft.

Between the crank bearing 9 and the shaft 25, a rotary and axially shiftable clutch member 37 is interposed, as shown in Fig. 2. At its ends the clutch member 37 is formed with tongues for engagement with corresponding cross grooves in the adjacent crank journal and in the shaft 25, one of the tongues being in constant engagement with one of the grooves, while the other tongue is movable into and out of engagement with the other groove. It is also formed with circular rack teeth, which are engaged by a pinion 38 on a shaft 39 passing through or into a transverse bore 40, formed in the crank and clutch case 5 and intersecting the clutch chamber, as shown in Figs. 2 and 3.

At its inner end the pinion shaft 39 has a bearing in a flanged cover and bearing member 42, fitting in the bore 40, and at its outer end it has a bearing in a flanged cover 43, which is bolted with a governor or controller case 44 to the crank and clutch case 5. The shaft 39 is provided, as shown in Figs. 3 and 12, with a pinion 45, meshing with a rack 46 guided in the governor case 130

44. The case 44 is formed at the upper end with a fluid pressure starting chamber 47, which is provided with a piston or movable part 48, to engage the upper end of the rack 46.

5 A spring 49, interposed between the lower end of the case 44 and rack 46, tends to move the rack upwardly and through the pinion shaft 39, to shift the clutch member 37 into 10 position, as shown in Fig. 2, to disconnect the compressor crank 8 from the drive shaft 25, and thereby render the compressor inoperative.

To hold the clutch member 37 in position 15 to operatively connect the compressor with the drive shaft 25, the governor or controller is provided, as shown in Fig. 12, with a pivoted trigger or latch 51, arranged to engage with a notch in or shoulder on 20 the rack 46, when it is shifted into position by the admission of fluid pressure into the chamber 47, to operatively connect the compressor with the drive shaft. The governor is also provided with a fluid pressure 25 stopping chamber 53, provided with a diaphragm or movable member 54, which is adapted when fluid pressure is admitted to said chamber, to thrust a pin 55 against the trigger or latch 51 and throw it out of 30 engagement with the rack 46, thereby permitting the spring 49 through the pinion shaft 39 to shift the clutch member 37 out of engagement with the drive shaft 25, as shown in Fig. 2. The trigger or latch 51 35 is normally held in engagement with the rack 46 by a spring pressed plunger 56, as shown in Fig. 12, and the pin 55 is retracted by a spring 57 interposed between a head or flange on the outer end of the pin, and 40 an adjusting nut 58, which is threaded in the inner end of the chamber 53 and in which the pin is guided adjacent its inner end.

The chamber 53 is connected by a pipe 45 59, as shown in Fig. 1, with the discharge valve chamber of the compressor.

The pinion shaft 39, projecting outwardly from the cover 43, is provided with a handle arm 60, for manually shifting the 50 clutch member 37 whenever there is insufficient pressure in the reservoir 3 for operating the governor or controller, or in case the governor or controller is out of order.

55 The distributing valve comprises a case consisting of a seat member 62 and a chambered cover 63 removably bolted therewith to the upward extension of the main case section 21 at the end opposite the crank and 60 clutch case 5. The seat member, which is fitted and held in a recess in the case section 21, as shown in Figs. 2 and 7, is formed with a central bore in axial alignment with the shaft 25, the reduced end of which extends into it. It is also formed, as shown

in Figs. 7 and 8, with ports 64 and passages registering with passages 65 in the case section 21, which are connected by pipes 66 with the engine cylinders, as shown in Figs. 1 and 5, through outwardly closing 70 check valves 67, like or similar to those described in Letters Patent 1,185,784.

The number and arrangement of the service and delivery ports and passages and their connections with the engine may be 75 varied according to the make or kind of engine and the number and arrangement of its cylinders.

A rotary valve disk 68, provided with a through port 69, is mounted and angularly 80 adjustable on the reduced threaded end of a spindle 70, which is rotatable and axially movable in the bore of the seat member 62, and has an eccentric axial slip tongue and groove connection with the drive shaft 25, 85 as shown in Figs. 2 and 7. The offset of the tongue and groove connection of the valve spindle and drive shaft from their center, prevents assembling and operative engagement of these parts except in a certain predetermined angular relation to each other.

The valve disk is locked in adjusted position on its spindle by a washer 72, loosely splined on the reduced end of the spindle and forced into engagement with the hub of 90 the valve disk by a nut 73. The face of the washer next to the valve disk is toothed, as shown in Fig. 11, to bite into the hub of the valve disk and prevent its slipping out of place, the washer being made of harder metal, such as steel, than the valve disk, which may be made of brass. A supply or inlet passage 75, formed as shown in Figs. 5, 6, 7 and 8, in the case section 21, valve seat 62 and cover 63, leads into the valve 100 chamber outside of the valve disk and is connected at its outer end by a pipe 76 with the driver's valve 18. The passage 75 communicates adjacent its outer end with the upper part of the carburetor chamber 110 through a passage 78, as shown in Fig. 6, the passage 75 being slightly restricted as compared with the bore of the pipe 76, so that the fuel oil in the carburetor chamber will be subjected to a slightly higher pressure than prevails in the passage 75 when compressed air is admitted to the starter unit.

A spray nozzle 80 extends upwardly from the lower part of the chamber 23 into the 120 passage 75 for carbureting the compressed air as it passes to the distributing valve. The nozzle is inserted in place and may be reached for inspection and for removing any obstruction therefrom, through an 125 opening in the case section 21 into the passage 75 opposite the nozzle, this opening being normally closed by a cap screw 81.

The passage 75 communicates, beyond its connection with the distributing valve 130

chamber, through a reduced passage 82 in the case section 21, with the upward extension of the carburetor chamber 23 on the opposite side of the gear chamber 22 from the 5 passage 78, so as to approximately equalize the pressure on the liquid fuel in the upper parts of the carburetor chamber, which are separated from each other by the intervening gear chamber.

10 The port 69 in the valve disk is arranged to register successively as the disk rotates, with the ports 64 in the valve seat, and when the disk is properly adjusted and timed, to admit charges of the compressed 15 carbureted air into the engine cylinders in the proper order at the beginning of the firing strokes of their pistons.

The valve disk 68 may be adjusted on its spindle and properly timed by setting the 20 piston of the engine cylinder or of the first cylinder, at the beginning of its firing stroke, then removing the cap 63, loosening the nut 73 and turning the disk on the spindle 70 till the port 69 begins to open into 25 the valve seat port 64, connected with the engine cylinder, finally tightening the nut to lock the valve disk in place on the spindle and replacing the cap 63.

To facilitate assembling the starter units 30 in the factory where they are made, for application to engines of a given make or kind, and the installation of such units with such engines by other mechanics, the valve disk is formed in its periphery, as shown in Fig. 35 5, with a setting hole 83, and the cover 63 is formed with setting holes 84, which are normally closed by cap screws 85, with either one of which the hole 84 registers, according to the direction of rotation of the 40 valve disk, when the port 69 is turned to its initial opening position relative to the port 64, connected with the engine cylinder or the first cylinder in firing order.

To properly set and time the distributing 45 valve for a given engine with which it is to be installed, the direction of rotation of the pump or other engine shaft with which the starter unit is to be connected, being known, the cap screw 85 closing the setting hole 84 for right or left hand rotation of the valve 50 disk 68, as the case may be, being removed, a nail or wire is inserted through the open hole 84, and the valve disk is rotated till the hole 83 therein registers with the hole containing the nail or wire, which will thereupon drop into the hole 83 and lock the 55 valve disk in its proper angular position, with its port 69 just beginning to open the port 64 connected with the first cylinder, as shown for example, in Fig. 5, for left hand or counterclockwise rotation of the valve disk. The compressor with the crank and clutch case 5, is then detached and removed from the main case section 21, with the 60 shaft 25 and its gear 26. The shaft 27 is

then turned till the slot in the coupling member 32 which is to be connected with the pump or engine shaft 34, is in a horizontal position corresponding with the standard practice of magneto setting. The 70 shaft 25 and the gear 26 are then replaced in engagement with the valve spindle 70 and pinion 28 respectively, without disturbing the angular position of the shaft 27 except possibly to the extent of a fraction of 75 the width of a gear tooth, to permit re-engagement of the gear with the pinion, the valve disk being locked and held immovably in its adjusted position, and the tongue and groove driving connection between the shaft 25 and the spindle 70 being engageable in only one angular relation to each other. The compressor with the crank and clutch case is then replaced and fastened to the case section 21. The valve disk is 80 thus properly adjusted at the factory where the starter is made, for installation with any given make or kind of engine, and is set and timed wherever it may be installed, by simply removing one of the cap screws 85 for right or left hand rotation, as the case may be, inserting a wire or nail in the open hole 84 and turning the valve disk by means of the shaft 27 till the wire or nail drops into the hole 83 in the disk. The 85 starter unit is then placed and fastened in position on the bracket or base plate 2, and the shaft is coupled with the pump or engine shaft 34, the wire or nail being removed from the hole 84, which is then 90 closed by its cap screw 85. The starter unit is thus installed without taking it apart.

Except during the brief operation of starting the engine with which it is connected, the valve disk 68 is held out of contact with its seat against shoulders in the cap 63, as shown in Fig. 2, by a light spring 86, inserted in an axial socket in the outer end of the shaft 25 and bearing at its outer end against the valve spindle 70. Unnecessary wear of the working face of the valve disk, which is constantly rotated while the engine runs, and of the valve seat are thus avoided.

The seat member 62 is fastened to the case 115 member 21 by a single screw 88, shown in Fig. 5, so that when desired, said member will remain in place when the cover 63 is removed.

The starting pressure-chamber 47 of the 120 governor or controller is connected by a pipe 91 with the pipe 76, which connects the distributing valve with the driver's valve 18.

The carburetor chamber 23 may be supplied with fuel oil through a filling cock 125 (not shown) inserted in an opening into the passage 78, which is shown in Fig. 5, and which communicates with the upper part of said chamber, as shown in Fig. 6. Preferably however, the apparatus is provided 130

with means for automatically supplying the carbureter chamber with fuel oil from a tank on the tractor, motor truck or car, thereby relieving the driver or operator

5 from special care or attention in this respect. For this purpose the apparatus is provided with a float chamber 93 and with a float 94.

The float chamber is connected at the bottom with the lower part of the carbureter 10 chamber 23 by an adaptor or fitting 95, as shown in Figs. 1 and 14, or it may be formed in a case 21' with the carbureter chamber 23, crank and clutch case, and other parts of the starter unit, as shown in 15 Figs. 16 and 17.

The connection between the float chamber and carbureter chamber is provided with a check valve 96, closing towards the float chamber and having a stem guided in a 20 cage 97, which is removably threaded in the bottom of the float chamber and formed at the lower end with a valve seat, the valve being held in place and its movement limited by a nut or collar fixed on the upper 25 end of the valve stem.

The top or upper part of the float chamber is connected by a pipe 98 with the fuel oil tank, and this pipe is provided, as shown in Fig. 1, with a shut-off cock 99.

30 The fuel supply pipe may be connected with a removable cover 100 of the float chamber, in which is threaded a removable valve cage and seat 101, provided with a valve 102, having a stem projecting downwardly into the upper part of the float chamber. The valve is held in place in the cage when the cover is removed and its movement is limited, by a screw 103, threaded in the lower part of the cage with its 35 head in position to engage with a collar on the valve stem.

The end of the pipe 98 connected with the float chamber, is provided with a strainer 104, and the upper reduced end of the cage 45 101 in which the valve is seated, is provided with a cap 105 to prevent impurities carried with the fuel oil from reaching the valve and interfering with its operation. Impurities deposited in the annular space below 50 the cap 105 may be removed from time to time by removing the cover 100 from the carbureter chamber and taking out the cage 101.

The cover 100 is formed with a vent opening 55 106 to the atmosphere, through which fuel oil will overflow in case the valve 102 leaks or fails to operate. The overflow of oil from this opening indicates trouble, and by closing the cock 99 in the fuel oil supply pipe 98, flooding of the carbureter, 60 starter unit and connections, may be avoided.

The driver's or controlling valve 18, as 65 shown in Fig. 13, comprises a case 108, formed with a flange 109 for fastening it

to the foot board of a truck or car, and provided with ports and pipe connections 110, 111 and 112, to which the pipes 19, 17 and 76 respectively, are attached.

The valve case is also formed with a valve 70 chamber 113 and inwardly directed seats at opposite ends thereof, and is provided with valves 114 and 115, guided therein by heads or enlargements 116 of their stems, and adapted to close in opposite directions 75 against the seats, to which they are normally held by a spring 117 interposed between the heads.

A push pin 119, guided in a nut 120 removably threaded in the upper end of the valve case, is adapted to open the valve 115. The push pin is flattened or formed with an air vent passage 121 on one side, and the upper end of the pin is formed or provided with a valve 122, fitted to a seat in the upper end of the nut 120. A push button 123 for operating the push pin 119 to open the valve 115 and close the valve 122, is guided in a cap 124, which is removably threaded on the upper end of the case 108 above the flange 109. The cap 124 is provided with a vent opening 125.

The lower part of the valve case containing the valve 114 is made in a separate section, which is threaded in or otherwise detachably fastened to the body of the case for convenience in construction and assemblage of parts of the device.

The reservoir port 110 communicates with the valve chamber 113 between the valves, the compressor port 111 communicates with the lower end of the valve chamber, which is normally closed by the valve 114, and the starter port 112 communicates with the upper end of the valve chamber, which is normally closed by the valve 115.

For lubrication of the moving parts of the starter unit without special care or attention on the part of the driver or operator, the cover and bearing member 42, as 100 shown in Figs. 3 and 4, is formed with an oil duct 128, which is connected at its outer end by a pipe 129 with the lubricating system of the truck or car on which the starting apparatus is installed.

As shown in Figs. 2 and 3, the lower part of the crank chamber 12 is connected with the gear chamber 22 by an oil duct 131, the upper parts of said chambers being connected by a passage 132 for equalizing the 105 pressure therein and avoiding interference with the circulation of lubricating oil through the starter unit.

The lower part of the clutch chamber 125 communicates with the duct 131 through an opening 133.

The bore in the valve seat member 62 is formed at its inner end with an annular recess, as shown in Figs. 2 and 7, in which is inserted a packing washer 135 of felt or 130

other suitable material, to prevent the free flow of oil through said bore into the distributing valve chamber, sufficient oil escaping past or through the washer, to properly lubricate the distributing valve disk 68 and its spindle 70. This washer also prevents the passage of fuel oil from the valve chamber into the gear chamber in case of an excess of fuel oil getting into the valve chamber through the passage 75 from the carbureter or from the pipes 66 leading to the engine.

As shown in Fig. 1, the lower part of the gear chamber 22 is connected by a drain or 15 outlet pipe 137 with the crank case of the engine.

In the operation of the apparatus, the reservoir 3 being charged with compressed air at a pressure, say of 225 pounds per 20 square inch, to start the engine the operator presses the push button 123 down with his foot. The push pin 119 being thus thrust downward, opens the valve 115 and closes the valve 122. Compressed air is 25 thus admitted from the reservoir through the pipe 19, pipe 76 and passage 75 into the distributing valve chamber outside of the rotary disk 68, which is incidentally pressed and held against its seat, as shown 30 in Fig. 7, by the fluid pressure on its outer face. As the engine when it stops, comes to rest with one of the pistons on its firing stroke, the port 69 in the valve disk 68 will open or partially open the port 64 in its 35 seat communicating with the engine cylinder of that piston, so that the compressed air carbureted in its passage to the distributing valve, will be delivered into the engine cylinder on the firing stroke, and 40 will be ignited by the ordinary electric ignition apparatus of the engine. The piston of the cylinder to which the explosive mixture is thus admitted being forced downward by the expansion of the compressed 45 fluid and its explosive force when ignited, starts the engine, and with it the distributing valve mechanism. As the valve disk 68 rotates, the port 69 registers 50 successively with the ports 64 in its seat, admitting to the several engine cylinders in proper firing order, compressed charges of 55 the explosive mixture of air and oil vapor, which are in turn ignited by the ignition apparatus of the engine, and exert their explosive force on the engine pistons.

Whenever compressed air is admitted to the distributing valve, it is also admitted through the passages 78 and 82 in the starter unit to the upper part of the carbureter chamber 23, in which it exerts a slightly greater pressure on the fuel oil than prevails in the passage 75, due to the slight restriction thereof as compared with the size or bore of the pipe 76. Fuel oil is 60 forced upwardly through the nozzle 80 and

discharged therefrom in a spray into the compressed air on its way to the distributing valve chamber, thereby producing an explosive mixture of the proper proportions just before it is delivered by the distributing valve to the engine.

With the opening of the valve 115 by the driver to supply compressed air to the distributing valve, compressed air is simultaneously admitted through the pipe 91 to the starting chamber 47 of the compressor governor and forces the movable part 48 downward against the tension of the spring 49. The clutch member 37 is thereby shifted by its connections with the governor hereinbefore described, to operatively connect the compressor with the drive shaft 25.

The compressor being thus started without care or attention on the part of the driver, delivers compressed air through the pipe 17 to the port in the lower end of the driver's valve, and when the pressure in the reservoir 3 is reduced below that produced by the compressor, the valve 114 will automatically open, permitting the compressed air to pass through the pipe 19 into the reservoir.

When the movable part 48 of the starting chamber 47 of the governor is shifted as above stated, to start the compressor, the rack 46 is locked by the trigger or latch 51 in position to hold the clutch member 37 in operative engagement with the drive shaft 25, and the compressor will continue to operate until the clutch member is released.

When the pressure in the reservoir 3 is restored or raised to a certain limit, which may be indicated by a pressure gage connected with the pipe 19 or reservoir, as shown in Fig. 1, the compressed air delivered from the reservoir or compressor through the pipe 59 into the chamber 53 of the governor, will compress the spring 57, shift the movable member 54 with the pin 55, thereby disengaging the trigger or latch 51 from the rack 46 and releasing the clutch member 37, which will thereupon be shifted by the spring 49 of the governor out of engagement with the drive shaft 25, thus stopping the compressor.

The maximum pressure with which the reservoir 3 is charged, and the limit at which the compressor will be automatically stopped, are determined by the adjustment of the nut 58 of the governor.

In case the compressor is operated at an abnormally high speed which might injure it, due to the racing of the engine with which it is connected, it will be automatically stopped by the governor before the predetermined maximum pressure is necessarily reached in the reservoir, by reason of the direct connection of the discharge valve chamber of the compressor with the

stopping chamber 53 of the governor and the greater resistance to the passage of compressed air from the compressor to the reservoir, due to the longer and sinuous connections between them through the driver's valve, resulting temporarily under such conditions, in a higher pressure in the stopping chamber of the governor than in the reservoir.

10 It it be desired at any time, in case compressed air is required for other purposes than starting, for instance, for the operation of air brakes, the compressor can be started when the engine is running to replenish the reservoir, by simply depressing the push button 123 of the driver's valve.

15 In case the pressure in the reservoir is exhausted or reduced below the limit at which it will operate the governor, the compressor can be started manually by means of the handle arm 60 of the clutch-shifting pinion shaft 39. The carbureter chamber 23 is kept supplied with fuel oil automatically through the float chamber 93, in which a substantially constant level is maintained by the float 94 closing the valve 102 when the oil rises in the float chamber above a certain level, and permitting the valve to open by gravity when the oil descends below that level.

20 When the distributing valve of the starter unit is not operating and the oil in the carbureter chamber 23 is not subjected to pressure, the level of the oil therein will be the same as that in the float chamber 93 and remain at that level, but when pressure is admitted to the carbureter chamber, it will be transmitted through the oil therein and through the connection between it and the float chamber and will close the check valve 96, which will remain closed, resulting in the lowering of the oil level in the carbureter chamber from which oil is drawn in the meantime for the operation of the starter

25 till the pressure is released from the carbureter chamber, whereupon the oil will rise in said chamber to the level of that in the float chamber. The descent of the oil level in the float chamber, causing the float 50 to descend, releases the valve 102, thereby admitting oil from the supply connection into the float chamber until the normal level therein and in the carbureter chamber 23 is restored.

30 The automatic check valve 96 in the connection between the carbureter chamber 23 and the float chamber 93 closing whenever compressed air is admitted to the carbureter chamber, prevents the float from being subjected to and collapsed or affected by the pressure required for the operation of the starting apparatus.

35 Lubrication of the starter unit is effected without attention on the part of the driver other than that required to maintain a sup-

ply of oil for the lubrication of the engine. Oil being supplied from the lubricating system of the engine by the pipe 129, Fig. 4, through the oil duct 128 in the member 42, passing into and flowing through the transverse bore 40 of the crank and clutch case 5 and thence into the longitudinal bore of said case and into the governor case 44 attached thereto, lubricates the clutch, the clutch-shifting mechanism, governor mechanism, drive shaft 25 and distributing valve. The oil passing through the crank bearing 9 into the crank chamber 12, is taken up by the crank 8 when the compressor is in operation, and splashed upwardly into the compressor cylinder and piston, thereby keeping the moving parts of the compressor lubricated. Oil passing through the bearing in the crank and clutch case around the shaft 25 and from the crank and clutch chambers through the duct 131 and opening 133 into the gear chamber 22, lubricates the gear and pinion therein. From the lower part of the gear chamber adjacent the pinion 28, oil passes to the bearings of the shaft 27, being prevented from escaping at the ends of the shaft by the packing washers 35. Surplus oil is discharged from the lower part of the gear chamber 22 through the pipe 137 into the crank case of the engine, from which it is taken up by the oil pump of the engine for further circulation through the lubricating system of the engine and starter apparatus.

40 The air vent passage 121 and opening 125 of the driver's valve 18 enable the carbureter chamber 23 to be automatically replenished from the float chamber 93 under atmospheric pressure when the push button 123 is released to permit the valve 115 to close and the valve 122 to open after each starting operation.

45 I claim:

1. In starting apparatus for internal combustion engines, the combination of a valve case provided with a seat having a port for connection with an engine cylinder, a rotary and axially movable valve disk fitting said seat and having a port adapted to register with the port in the seat, means 110 tending to shift the valve disk out of contact with its seat, means for rotating the valve disk, and a chamber formed by the valve case on the opposite side of the valve disk from its seat and having a fluid pressure supply connection, the valve disk being adapted to be shifted and held against its seat when fluid under pressure is admitted to said chamber.

2. In starting apparatus for internal combustion engines, the combination of a valve case provided with a seat having a port for connection with an engine cylinder, a rotary and axially movable distributing valve disk fitting said seat and having a port adapted 125

- to register with the port in the seat, means tending to shift and hold the valve disk out of contact with its seat, a chamber formed by the valve case on the opposite side of the valve disk from its seat and having a fluid pressure supply connection, the valve disk being adapted to be shifted and held against its seat when fluid under pressure is admitted to said chamber, and a shaft arranged 10 in axial alignment with the valve disk and having an axial slip connection therewith.
3. In starting apparatus for internal combustion engines, the combination of a valve case provided with a seat having a port for connection with an engine cylinder, a rotary valve spindle journaled and axially movable in said case, a distributing valve disk, mounted and angularly adjustable on the spindle and having a port arranged to register with the port in the seat, means tending to shift and hold the valve disk out of contact with its seat, a chamber formed by the case on the opposite side of the valve disk from its seat and having a fluid pressure supply connection for shifting and holding the valve disk against its seat when fluid under pressure is admitted to the chamber, a drive shaft arranged in axial alignment with the valve spindle and having 20 a detachable eccentric axial-slip driving connection with the spindle.
4. In starting apparatus for internal combustion engines, the combination of a chamber provided with a seat having a port for connection with an engine cylinder, a shoul- 30 dered valve spindle journaled and movable axially in said case and having a reduced threaded end, a distributing valve-disk mounted and angularly adjustable on the reduced end of the spindle and having a port arranged to register with the port in the seat, a toothed locking washer keyed on and adjustable lengthwise of the spindle, a clamping nut threaded on the spindle and adapted to force the washer into locking engagement with the valve disk, and means for rotating said spindle and disk.
5. In starting apparatus for internal combustion engines, the combination of a case 50 provided with a valve seat having a port for connection with an engine cylinder, a valve spindle journaled and axially movable in said seat, a valve disk mounted and angularly adjustable on said spindle and having a port arranged to register with the port in the seat, a chamber formed by the case on the opposite side of the valve disk from its seat and having a fluid pressure supply connection, means tending to shift 60 and hold the valve disk out of contact with its seat, said valve disk being adapted to be shifted and held against its seat by fluid pressure admitted to said chamber, a primary drive shaft mounted in the case in axial alignment with the valve spindle and
- having an axial slip driving connection with said spindle, and a secondary drive and coupling shaft connected with the primary shaft by gears and provided at its ends with members of tongue and groove couplings set 70 at right angles to each other.
6. In starting apparatus for internal combustion engines, the combination of a valve case provided with a valve seat having a port for connection with an engine cylinder, a rotary distributing valve disk provided with a setting hole and with a port arranged to register periodically with the port in said seat as the disk rotates, a primary drive shaft arranged in axial alignment with the valve disk and having an axially separable driving connection therewith, and a secondary drive shaft geared with the other shaft and provided with a coupling member, the valve case having a setting hole arranged to register with the setting hole in the valve disk when the port in the valve disk is in its initial opening position relative to the port in the valve seat, and the primary drive shaft with its gear being removable lengthwise from engagement with the valve disk and the secondary drive shaft to change the angular relation between the valve disk and the coupling member of the secondary drive shaft. 80
7. In starting apparatus for internal combustion engines, the combination of a valve case provided with a valve seat having a port for connection with an engine cylinder, a rotary distributing valve disk provided with a setting hole and with a port arranged to register periodically with the port in said seat as the disk rotates, a primary drive shaft arranged in axial alignment with the valve disk and having an axially separable driving connection therewith, and a secondary drive shaft geared with the other shaft and provided with a coupling member, the valve case having two setting holes arranged to register with the setting hole in the valve disk when the disk is rotated in opposite directions and the port therein is in its initial opening position relative to the port in the seat, and the primary shaft with its gear being removable lengthwise from engagement with the valve disk and the gear of the secondary shaft to change the angular relation between the valve disk and the coupling member of the secondary drive shaft. 90
8. In starting apparatus for internal combustion engines, the combination of a case composed of separable sections and provided with a valve seat having a port for connection with an engine cylinder, a valve spindle journaled and axially movable in said seat, a valve disk fixed on said spindle and having a port arranged to register periodically with the port in the seat, a chamber formed by the case on the opposite 100
- 105
- 110
- 115
- 120
- 125
- 130

- side of the valve disk from its seat and having a fluid pressure supply connection, means tending to shift and hold the valve disk out of contact with its seat, said valve disk being adapted to be shifted and held against its seat by fluid pressure admitted to said chamber, a primary drive shaft mounted in said case in axial alignment with the valve spindle and having an eccentric axial slip section, and a valve case detachably fastened to the opposite end of the base section; a primary drive shaft provided with bearings in the base section and crank case; a crank having bearings in the crank case 70 in axial alignment with said shaft; a clutch mounted in the crank case for detachably connecting said crank and shaft; a compressor cylinder mounted on the crank case and having a piston connected with the 75 crank; a rotary distributing valve disk mounted in the valve case in axial alignment with said shaft and detachably connected therewith; and a secondary drive shaft mounted in the base section and provided with coupling members at the ends and geared with the primary drive shaft; the crank case with the compressor and the valve case with the distributing valve being removable from the base section without disturbing its mounting or the connections of the secondary shaft. 80
- 10 driving connection therewith, a secondary drive and coupling shaft mounted in said case parallel with the other shaft and provided at its ends with members of tongue and groove couplings set at right angles to each other and gears connecting said shafts with each other, the valve disk and its case being formed with holes which register with each other when the port in the disk is in its initial opening position, and the primary 85 shaft with its gear being removable from engagement with the valve spindle and the gear of the secondary shaft.
9. In starting apparatus for internal combustion engines, the combination of a main case section provided with a mounting base and at one end with a valve case having a seat with a port for connection with an engine cylinder, a compressor comprising a crank and clutch case removably mounted 90 on the other end of the main case section, a rotary distributing valve fitting said seat and having a port arranged to register periodically with the port in the seat as the disk rotates, a primary drive shaft journaled in the 95 crank and clutch case in axial alignment 100 in the main case section and valve case in axial alignment with the valve disk and having an axially separable driving connection with said disk, a crank journaled in the crank and clutch case in axial alignment with said shaft, a clutch for connecting the crank with said shaft, means for shifting the clutch, a secondary drive shaft mounted in the main case and provided at the ends with coupling members, and gears connecting 105 said shafts with each other.
10. In starting apparatus for internal combustion engines, the combination of a crank case open at one end and side and provided with a removable end cover, a drive shaft mounted in said case, a crank having bearings in said case in axial alignment with the drive shaft and detachably connected with the drive shaft, a compressor cylinder removably mounted on said case 110 over the side opening therein and provided with a piston connected by a rod with the crank, the crank and connecting rod being removable bodily with the cylinder and piston from the crank case and drive shaft through the side and end opening in the 115 crank case when the cover is detached.
11. In starting apparatus for internal combustion engines, the combination of a case comprising a base section, a crank case detachably fastened to one end of the base 120 section, and a valve case detachably fastened to the opposite end of the base section; a primary drive shaft provided with bearings in the base section and crank case; a crank having bearings in the crank case 125 in axial alignment with said shaft; a clutch mounted in the crank case for detachably connecting said crank and shaft; a compressor cylinder mounted on the crank case and having a piston connected with the crank; a rotary distributing valve disk mounted in the valve case in axial alignment with said shaft and detachably connected therewith; and a secondary drive shaft mounted in the base section and provided with coupling members at the ends and geared with the primary drive shaft; the crank case with the compressor and the valve case with the distributing valve being removable from the base section without disturbing its mounting or the connections of the secondary shaft.
12. In starting apparatus for internal combustion engines, the combination of a distributing valve having a compressed air supply connection, a carburetor comprising a chamber and adapted to carburet the compressed air supplied to the distributing valve, a float chamber the lower part of which is connected with the lower part of the carburetor chamber, a valve in the connection between said chambers adapted to close when pressure is admitted to the carburetor chamber, a liquid fuel supply connection with the float chamber, a valve in the supply connection, and a float adapted to close the supply valve when liquid rises to a certain level in the float chamber. 130
13. In starting apparatus for internal combustion engines, the combination of distributing valve mechanism adapted to supply an explosive mixture to an engine cylinder on the firing strokes of its piston and having a compressed air supply connection, a carburetor chamber having a compressed air supply connection with the upper part thereof and a spray nozzle opening into the compressed air supply connection of the distributing valve mechanism, a float chamber having a vent opening in the upper part thereof and a connection between the lower part thereof and the lower part of the carburetor chamber provided with a check valve closing towards the float chamber, a liquid fuel supply connection with the float chamber provided with a valve, and a float adapted to close the valve in the fuel supply connection when the liquid rises to a certain level in the float chamber. 135
14. In starting apparatus for internal combustion engines, the combination of a compressed air reservoir, a compressor connected with the reservoir, distributing valve mechanism connected with the reservoir, a governor comprising a pressure chamber 140

connected with the reservoir, and a movable part adapted to start the compressor whenever pressure is admitted to said chamber, fluid pressure actuated means connected 5 with the reservoir and adapted to automatically stop the compressor whenever the pressure in the reservoir is raised to a certain point and a controlling valve adapted to simultaneously open communication from 10 the reservoir to the distributing valve mechanism and to the governor.

15. In starting apparatus for internal combustion engines, the combination of a main case section containing a carburetor chamber and having a mounting base and parallel shaft bearings, a crank case removably mounted on one end of the main case section and having bearings in alignment with one of the bearings therein, a valve case removably mounted on the other end of the main case section, a primary drive shaft mounted in aligned bearings of the main case section and crank case, a compressor crank mounted in the crank case in axial alignment 25 with the primary drive shaft with which it has a separable driving connection, a compressor cylinder mounted on and removable with the crank case from the main case section and provided with a piston connected 30 with the crank, a distributing valve having a rotary spindle mounted in and removable with the valve case from the main case section in axial alignment with the primary drive shaft with which the valve spindle has a 35 separable driving connection, a secondary drive shaft mounted in the base of the main case section and provided at the ends with coupling members, gears connecting the drive shafts, and compressed air supply, liquid fuel supply, and explosive mixture delivery pipe connections attached to the main base section, the crank case with the compressor and the valve case with the distributing valve being removable without disturbing the mounting and pipe connections 40 of the main base section and the coupling connections of the secondary drive shaft.

16. In starting apparatus for internal combustion engines, the combination of a case 50 containing crank, gear and valve chambers communicating with one another through axially aligned shaft and crank bearings; a compressor cylinder mounted on the upper part of the case and opening into the crank chamber; a primary drive shaft, crank, and valve spindle mounted in said bearings, a secondary drive shaft mounted in the case below the primary drive shaft and connected therewith by gears, an oil supply connection leading into the case between the crank and gear chambers, an oil duct leading from the lower part of the crank chamber into the gear chamber, and an oil outlet connection leading out of the lower part 60 of the gear chamber.

17. In starting apparatus for internal combustion engines, the combination of a case containing crank, gear, clutch and valve chambers communicating with one another through aligned openings, the case having 70 a transverse bore intersecting the clutch chamber; a primary drive shaft, crank and valve spindle having bearings in said openings; a shiftable clutch member for connecting the crank with said drive shaft; a clutch 75 shifting shaft mounted in the transverse bore of the case; a closure for one end of the transverse bore provided with an oil supply connection and a passage leading therefrom into the bore; a secondary drive shaft 80 mounted in the case below the primary drive shaft and connected therewith by gears enclosed in said gear chamber; an oil duct leading from the crank case into the gear chamber between the drive shafts; and an 85 oil outlet connection leading from the gear chamber below said duct.

18. In starting apparatus for internal combustion engines, the combination of a reservoir; a compressor; distributing valve 90 mechanism; and a controlling valve comprising a case having connections with the reservoir, compressor and distributing valve mechanism, valve disks opening in opposite directions towards the reservoir connection 95 between them; means tending to close the valve disks; the connections with the compressor and with the distributing valve mechanism being made with the case on opposite sides of the valve disks from the reservoir connection; and a push pin for 100 opening the valve disk, which controls the connection with the distributing valve mechanism, provided with a passage which opens said connection to atmosphere when the valve disk is closed and with a valve for 105 closing said passage when said valve disk is open.

19. In starting apparatus for internal combustion engines, the combination of a compressed air reservoir, distributing valve 110 mechanism; a compressor; a governor comprising a pressure starting chamber and a movable part adapted to start the compressor when fluid pressure is admitted to the chamber; and a controlling valve comprising a case having connections with the reservoir, distributing valve mechanism and governor, oppositely seating valve disks on 115 opposite sides of and opening towards the reservoir connection, means tending to close the valve disks, the connections with the distributing valve mechanism, compressor and governor being made with the case on opposite sides of the valve disks from the reservoir connection, and means for opening at will the valve disk which controls the connection with the distributing valve mechanism and governor.

20. In starting apparatus for internal 130

- combustion engines, the combination of a compressed air reservoir; distributing valve mechanism; a compressor; a governor comprising a stopping chamber connected with the discharge side of the compressor, a starting chamber, and a controlling valve comprising a case having connections with the reservoir, distributing valve mechanism and starting chamber of the governor, oppositely seating valve disks on opposite sides of and opening towards the reservoir connection, means tending to close the valve disks, the connections with the distributing valve mechanism and the starting chamber of the governor and with the compressor being made with the case on opposite sides of the disks from the reservoir connection, and means for opening at will the valve disk which controls the connection with the distributing valve mechanism and governor.
21. In starting apparatus for internal combustion engines, the combination of distributing valve mechanism comprising a case and a rotary member provided with setting holes registering with each other when the rotary member is in position to deliver starting fluid to an engine cylinder at the beginning of the firing stroke of its piston, a drive shaft provided with a coupling member for connection with an engine shaft, and an adjustable transmission connection between said rotary member and drive shaft.
22. In starting apparatus for internal combustion engines, the combination of a distributing valve case provided with setting holes for right and left rotation, a rotary member provided with a setting hole registering with either setting hole in the case according to the direction of rotation of said member when it is in position to deliver starting fluid to an engine cylinder at the beginning of the firing stroke of its piston, a drive shaft provided with a coupling member for connection with an engine shaft and an adjustable transmission connection between said rotary member and drive shaft.
23. In starting apparatus for internal combustion engines, the combination of a reservoir, a compressor, a distributing valve and a controlling valve comprising a case having connections with the reservoir, compressor and distributing valve, valve disks opening towards the reservoir connection, one controlling the connection with the compressor and the other the connection with the distributing valve, means tending to close the valve disks, and means for opening at will the valve disk which controls the connection between the distributing valve and reservoir.
24. In starting apparatus for internal combustion engines, the combination of an enclosed rotary distributing valve member adapted to admit in successive charges compressed starting fluid to an engine cylinder on the firing strokes of its piston, a drive shaft provided at the ends with coupling members set at right angles to each other, and a releasable or adjustable transmission connection between said distributing valve member and shaft, whereby the angular relation of said distributing valve member to the coupling members may be changed.

In witness whereof I hereto affix my signature.

NIELS A. CHRISTENSEN.
